UNITED STATES PATENT OFFICE.

OTTO PETERMANN, OF GROTON, NEW YORK, ASSIGNOR TO STANDARD TYPEWRITER COMPANY, OF GROTON, NEW YORK, A CORPORATION OF NEW YORK.

KEYBOARD.

1,081,144.

Specification of Letters Patent.

Patented Dec. 9, 1913.

Application filed May 12, 1911. Serial No. 626,729.

To all whom it may concern:

Be it known that I, OTTO PETERMANN, a citizen of the Republic of Switzerland, and a resident of Groton, county of Tompkins, 5 and State of New York, have invented certain new and useful Improvements in Keyboards, of which the following is a full, clear, and exact description.

This invention relates more particularly 10 to key-levers, and especially to key-levers adapted for use in connection with foldable front strike typewriting machines.

One of the principal objects of the invention is to provide a key-lever which may be 15 made in a single piece from light sheet metal, and which is so constructed that it will be very strong and at the same time provide a substantial bearing for each key-lever.

20 Another object of the invention is to provide a key-lever having its body and bearing lugs corrugated and provided with extended integral bearings pressed or formed from said bearing parts.

25 A further object of the invention is to provide key-levers which are so constructed that they may be arranged in banks or sets and be suspended from a support, and which are so arranged that the type-bars may lie 30 in a substantially horizontal plane with respect thereto.

With these and other objects in view, the invention will be hereinafter more particularly described with reference to the accompanying drawings, which form a part of this specification, and will then be pointed out in the claims at the end of the description.

35 In the drawings, Figure 1 is a longitudinal section of one form of machine showing one embodiment of my invention. Fig. 2 is a detail view of the blank for one of the key-levers, the said key-lever being complete except that one of the bearing parts has not 40 been bent over into alinement with the other bearing part. Fig. 3 is a detail plan view of one of the key-levers; and Fig. 4 is a transverse section through the bearing parts taken on the line IV—IV of Fig. 3.

45 While I show the invention as applied to

a particular form of machine in which the carriage and platen are adapted to fold forward, it will be understood that the invention may be applied to any of the various forms of typewriting or like machines.

55

The frame 10 may be of any suitable construction and mounted thereon is a support 11 on which is a carriage bed 12. A carriage 13 is adapted to travel along the bed 12, and rotatably held on said carriage is a 60 platen 14. The support 11 may be formed of two parts pivoted together, as at 15, and one of these parts together with the platen and carriage may be folded forward over the key-levers, and said support as well as 65 the carriage and platen may be moved vertically with the slides 16 or otherwise. At the rear of the frame are a plurality of brackets 17, and pivotally held at 18 to these brackets are the type-bars 19, the latter being supported at the forward end on a curved bar or plate 20, and each type-bar being provided with a type-head having suitable characters thereon for printing purposes. The parts thus far described may 70 be of the usual or of any preferred construction.

A plurality of key-levers 21 are arranged in groups and each group or bank of levers is adapted to be supported from one of the 80 transversely-extending rods 22. Each key-lever has a substantially horizontally arranged body 23, a part of which may be angularly formed, as at 24, and said angular portion may have an upturned end 25 in 85 which is an aperture 26. A link 27 has one end held in the aperture 26 and the other end held to one of the type-bars 19 at a point adjacent to but to one side of the pivot 18. Each key-lever has its body corrugated 90 lengthwise thereof, as by depressing the same substantially centrally thereof to form a rib 28, and this rib extends outward and upward conforming to the outer end 29 of the key-lever, on which end is a part 30 95 serving as a finger or key portion for said lever. The part 30 is formed from the same piece of steel or other metal as the body 23 and has a flange as 31 to receive the paper piece which indicates the character, a bol- 100

ster of paper or other material, the glass or celluloid disk, and the retaining cap usually employed in connection with key-levers. This part 30 has a corrugation 31 extending into the body a short distance which serves to materially stiffen the angle portion of said part.

The key-levers are each provided with a bearing lug 32 and a second bearing lug 33 which are spaced apart and connected together by an integral bar 34. The bearing lug 33 is located above the body of the key-lever so that the said key-lever may be suspended from its support, as one of the rods 22, and said bearing lugs 32 and 33 form a suspending head and are arranged in alignment as shown in Figs. 3 and 4 in such a way that the bar 34 will lie in a normally horizontal plane while in use. Each bearing lug is provided with an aperture 35, and each aperture is formed by pressing or forming from each bearing lug a bearing 36 which forms a substantial and extended bearing surface for each bearing lug. These bearings 36 are annular in form and may project somewhat beyond the sides of the bearing lugs and outwardly therefrom, and around each bearing 36 is a depression forming a rib or corrugation 37. These annular corrugations are connected by a rib 38 which extends along the connecting or spacing bar 34, and the annular rib or corrugated part of the bearing lug 32 is connected to and forms a continuation of the corrugated rib 28 of the body of the key-lever, though it will be understood that instead of the corrugations being formed as a single rib, they may be otherwise made as desired.

Each key-lever has an apertured lug 39 located on the under edge thereof and slightly in advance of the pivot of the key-lever, and held in the aperture of said lug is one end of the spring 40, the other end of said spring being held to a transversely-extending bar or plate 41.

From the foregoing, it will be seen that a very strong, light key-lever is provided which may be made of a single piece of sheet steel or other metal; that by forming the bearing lugs with the extended annular bearings, a bearing surface much greater in extent than the thickness of the material is provided for each key-lever; that said key-levers may be arranged in banks or sets; that said key-levers may be utilized to self-space the same, and that said key-levers may be readily and cheaply made.

Having thus described my invention, I claim as new and desire to secure by Letters Patent:—

1. In a typewriting machine, a key-lever having a body provided with a rib lengthwise thereof, two alined bearing lugs ar-

ranged above said body, and integral bearings projecting from said bearing lugs. 65

2. In a typewriting machine, a key-lever having a corrugated body and two alined integral and suspending bearing lugs each having an extended integral bearing. 70

3. In a typewriting machine, a key-lever having a corrugated body, and integral corrugated and suspending bearing lugs. 75

4. In a typewriting machine, a key-lever formed of a single piece of metal and comprising a thin sheet metal body provided with an angular end for attachment to a type-bar and its other end provided with means as a key portion for said lever, bearing lugs located above the body, a bar projecting from one bearing lug on one side of the body for spacing said bearing lugs apart, said bearing lugs having extended bearings pressed therefrom, and corrugations extending along the body portion, the bearing lugs and the spacing bar. 80

5. In a typewriting machine, a key-lever having a sheet metal body portion provided with an end for attachment to a type-bar and its other end provided with means as a key portion for said lever, bearing lugs, and a bar for spacing said bearing lugs, said bearing lugs having annular bearings pressed therefrom. 90

6. In a typewriting machine, the combination with a transverse rod extending across the machine, of a key-lever having an extended body and provided with an integral suspending head having apertured and spaced bearing lugs connected together 100 and arranged intermediate the ends of the body and fitting over said rod, said key-lever being provided with a corrugated body. 95

7. In a typewriting machine, a key-lever made of a single piece of metal having a substantially horizontally-extending body portion and an integral suspending head comprising a bearing lug extending from one edge of the lever body and provided with an aperture, an integral reach and spacing bar located at the upper edge of said bearing lug and at right angles thereto, and a bearing lug at right angles to the reach bar and having an aperture in alignment with the aperture of the other bearing lug, all of which are corrugated. 110

8. In a typewriting machine, a key-lever provided with a corrugated and horizontally arranged body and a suspending head located between the ends of said body and having spaced and apertured bearing lugs connected together. 120

9. In a typewriting machine, a key-lever having an integral suspending head provided with spaced bearing lugs, a bar connecting said lugs, and extended annular bearings pressed from said bearing lugs. 125

10. In a typewriting machine, a key-lever

having a corrugated body and an integral corrugated suspending head located intermediate the ends of said body and comprising two lugs spaced apart, and a bar connecting said lugs and projecting from one side only of said body.

5 11. In a typewriting machine, a key-lever having a corrugated body and an integral

corrugated suspending head located between the ends of said body. ¹⁰

This specification signed and witnessed this 8th day of May A. D. 1911.
